METHOD OF MAKING PILE FABRICS

John Crawford, Amsterdam, N. Y., assignor, by mesne assignments, to Mohasco Industries, Inc., Amsterdam, N. Y., a corporation of New York

Application January 4, 1955, Serial No. 479,713

6 Claims. (Cl. 139—39)

This invention relates to the production of pile fabric floor coverings or carpets by weaving operations on looms utilizing pile wires and equipped with a jacquard mechanism and, more particularly, the invention is concerned with a novel method of weaving carpets of two-shot construction having a wide variety of pile surface effects. The new method does not require the use of additional jacquard cards or involve mispicking, so that the use of the method does not subject the jacquard mechanism to unusual wear or impair the efficiency of the weaving operation. Also only minor changes are required in a conventional loom, when it is to be used to weave in accordance with the method, and such changes can be made quickly and without difficulty.

The carpets produced by the method have a pile made up of loops of pile yarns, which have been raised selectively and in accordance with a pattern over one, two, or more wires before again being bound into the fabric beneath a weft shot. When the wires are withdrawn, the loops assume final heights varying with the number of wires, over which they were raised, and the fabric thus has high and low loops distributed as determined by the pattern. The pile yarns may be bound in beneath weft shots in the upper series, that is, those lying above the stuffer warp yarns, or the pile yarns may pass to the back of the fabric and be bound beneath weft shots in the lower series beneath the stuffer warps to produce a pattern-on-the-back weave, as desired.

The jacquard mechanisms employed on looms used in the practice of the new method may be of various kinds, but a mechanism provided with a lash knot board and a comber board functions well for the purpose and an example of the method, in which a loom having such a mechanism is used, will be illustrated and described in detail for purposes of explanation.

For a better understanding of the invention, reference may be made to the accompanying drawings, in which

Figs. 1-3, inclusive, are diagrammatic views illustrating the operation of the jacquard mechanism at different stages in the cycle of operations of a loom functioning in accordance with the new method;

Figs. 4 and 5 are fragmentary plan views of the knot and comber boards, respectively, of the jacquard mechanism;

Figs. 6-9, inclusive, are diagrammatic longitudinal sectional views showing the relative positions of the elements of the fabric in the four sheds formed in the stages making up the loom cycle;

Fig. 10 is an exploded perspective view of a typical fabric produced by the new method;

Fig. 11 is a longitudinal sectional view of the fabric shown in Fig. 10.

The fabric illustrated in the drawings is of typical two-shot construction and includes stuffer warp yarns 20 in groups of three ends each, pile warp yarns 21, and binder warp yarns 22 and 23 in two sets. The warp yarns are interwoven with weft yarns 24, 25 in upper and lower

2

series lying, respectively, above and below the stuffer warp yarns 20 and bound in place by the binder warp yarns in the usual way. In the production of the fabric, the pile yarns 21 are raised over pile wires 26 to form pile loops and certain of the pile yarns pass over two or more consecutive wires to form multiple or float loops, as determined by the pattern carried by the cards of the jacquard mechanism.

In the weaving of the fabric illustrated, the warp yarns are manipulated to form sheds in four stages, which constitute a cycle of loom operation. In the formation of the sheds, the pile yarns are handled by the jacquard mechanism, while the stuffer and binder warp yarns are raised and lowered by the usual harnesses. The jacquard mechanism illustrated includes a comber board 27 having an opening 27a for the passage of each of the tail cords 28 of the mechanism and each tail cord has an eye 29, through which a pile yarn passes, and carries a lingo 30 at its lower end. Just above the comber board, each tail cord has a knot 31 of such a size that it will not pass through an opening 27a in the board and, above the knots, the cords pass through the eyes of respective needles 32 of the jacquard mechanism. Above the needles, the cords pass through keyhole openings 33a in a lash knot board 33 and the cords have knots 34 above the knot board, which can pass through the circular parts of the openings 33a but not through the slotted portions of the openings. The upper ends of the cords are attached to a suitable fixed support 35. The needles 32 are urged to their normal positions shown in Fig. 1 by the usual springs and the needles are moved selectively from such positions by the pattern cards, such as card 36, customarily employed in a jacquard mechanism.

In an ordinary jacquard mechanism of the type having a knot board and a comber board, the boards move upwardly at the proper times in the loom cycle to raise the pile yarns and the knot board rises more rapidly than the comber board. The knot board raises the lash, that is, the pile yarns, which are to lie in the top line of a shed and form loops over a pile wire, while the comber board ordinarily raises the remaining pile yarns only into the bosom, that is, into line with the stuffer warp yarns, so that these pile yarns do not pass over the wire. Before the boards begin to move upward, the cylinder of the jacquard mechanism moves a card against the end of the needles and those needles, which engage a solid part of the card, are moved endwise. The needles so moved shift the tail cords controlled thereby laterally, so that the upper knots in the cords overlie the slots of the openings in the knot board and are thus in position to be engaged by the board. When the boards rise, the cords, which have been shifted by the needles, are raised by the knot board and raise their pile yarns, while the upper knots on the unshifted cords pass through the openings in the board, so that those cords are not raised by the knot board. All tail cords not raised by the knot board are raised by the comber board and, when the boards move down, all the cords are lowered together by the boards, so that all the pile yarns return to their original positions.

When a loom with a jacquard mechanism constructed and operating as above described is to be employed in the practice of the method of the invention, the cam used for raising and lowering the knot board is shifted rearwardly on the cam shaft. As a result, when the boards move down to lower the pile yarns after insertion of a pile wire in the shed beneath the yarns, the knot board lags behind the comber board for a purpose to be described. The only other change to be made in the loom is the replacement of the cam operating the comber board by another having a higher lift, so that all pile yarns,

whose tail cords are lifted by the comber board, will be raised to form part of the lash, and will thus lie at such a level that a pile wire can be inserted beneath them.

The stages in a cycle of operations of a loom weaving in accordance with the method of the invention will be apparent from an examination of Figs. 6-9, incl., which show the handling of two pile yarns, a group of three stuffer warp yarns, and a binder warp yarn of each set. In the cycle, one pile yarn is caused to form a double loop, while the other forms two single loops. In Fig. 6, there is illustrated a shed, in which pile yarn 21a has been raised to the top line by the knot board and pile yarn 21b has been raised to the top line by the comber board. The stuffer warp yarns 20 and the binder warp yarns 23 of the first set lie in the center line of the shed, while the binder warp yarns 24 of the second set lie in the bottom line of the shed. Upon formation of the shed as described, a wire 26 is inserted beneath the lash made up of all the pile yarns represented by yarns 21a, 21b and above the stuffer warp yarns 20 and the binder warp yarns 23 of the first set. Also, a shot of weft yarn 25 is inserted beneath the stuffer warp yarns 20 and the binder warp yarns 23 and above the binder warp yarns 24 of the second set. Upon insertion of the wire and the weft shot, the wire and shot are beaten up to the fell of the goods, following which the shed is changed and the second shed shown in Fig. 7 is formed.

In the formation of the shed of Fig. 7, the binder warp yarns 20 are moved down, as are also the pile yarns. In such downward movement of the pile yarns, the yarn 21b, which was raised by the comber board, moves down ahead of the yarn 21a, which was raised by the knot board, so that the yarn 21b reaches its lowermost position, while the downward movement of the yarn 21a is continuing. The relative positions of the binder warp yarns 23 and 24 remain unchanged and, when the yarn 21b has reached its bottom position and while the yarn 21a is still moving down, a shed is formed, in which the pile yarn 21a and the binder warp yarns 23 lie in the top line and the binder warp yarns 24, the stuffer warp yarns 20, and the pile yarn 21b are in the bottom line. A shot of weft yarn 25 is then inserted into this shed and the throw of the shuttle is so timed, that the weft shot passes beneath the descending yarn 21a. The inserted weft shot is then beaten up and it binds the yarn 21b but does not bind the yarn 21a. By the time both the comber and knot boards have reached their lowermost positions, the card has been moved away from the bank of needles, so that the needles and their tail cords have returned to their initial positions.

Before the formation of the third shed, the next card is advanced into active position on the cylinder of the jacquard mechanism and is moved into contact with the needles 32. In the cycle being described, the pile yarn 21a is to form a double loop and pile yarn 21b is to form two single loops. Accordingly, the second card is cut with holes opposite the needles controlling the tail cords of both yarns 21a and 21b and the needles and tail cords will not be shifted, when the card engages the bank of needles. When the knot board rises, the yarn 21a will not be raised by that board, as in the first stage of the cycle, but will be raised with yarn 21b by the comber board. The third shed of the cycle is thus the same as the first shed shown in Fig. 6, except that the binder warp yarns 24 are raised to the center line of the shed and the binder warp yarns 23 lie in the lower line. A pile wire 26 and a shot of weft yarn 25 are inserted in to the third shed and beaten up, after which the warp yarns are manipulated to form the fourth shed illustrated in Fig. 9.

In the formation of the shed of Fig. 9, the stuffer warp yarns 20 and the pile yarns 21a, 21b are moved down while the relative positions of the binder warp yarns 23, 24 remain unchanged. As the pile yarns were raised by the comber board, they move down together and, when

the new shed is ready for insertion of a shot of weft yarn 25, the binder warp yarns 24 lie in the upper line of the shed and all the other warp yarns lie in the lower line. When the inserted shot of weft is then beaten up, 5 pile yarns 21a, 21b are bound thereby. The cycle of operations is thus completed and a new cycle started with the formation of the shed shown in Fig. 6.

In weaving in accordance with the new method, yarns typified by yarn 21a, which are raised by the knot board 10 in the formation of a shed, are not bound in the fabric by the weft shot inserted into the following shed, because of the late descent of the knot board. If such yarns are raised by the comber board in the formation of the third shed, they will be bound into the fabric by the weft 15 shot inserted into the fourth shed and each such yarn will thus provide a double loop in the pile. If a yarn is to form a triple loop, it will be raised twice in succession by the knot board before being raised by the comber board and, by proper cutting of the jacquard cards, any yarn 20 can be caused to form a loop of any size desired. Yarns represented by yarn 21b which are to form single loops, are raised by the comber board and such yarns are bound in the fabric by the weft shots inserted into the sheds 25 following those in which the yarns were raised.

In describing the cycle illustrated in Figs. 6-9, incl., it has been assumed that all the pile yarns in the fabric are typified by the yarns 21a, 21b and that the fabric is to contain no loops larger than double loops. It is to be understood, however, that, each time the pile yarns 30 are raised for insertion of a wire beneath them, the elevation of the yarns may be effected by the action of either the comber board or the knot board, as may be determined by the pattern. Accordingly, by properly cutting the jacquard cards, it is possible to cause the pile yarns 35 to form multiple loops over any desired number of wires and the relative positions of single and multiple loops of different yarns in the pile may be varied, as desired.

A typical fabric produced by the method of the invention is illustrated in Figs. 10 and 11. The fabric has 40 the backing construction previously described and the pile yarns have been raised over wires under the control of the pattern, so that the yarn 21c has been caused to form a succession of loops which, in the length of fabric shown, comprises a double loop, a single loop, two 45 double loops, a single loop, and a double loop in the order stated. The yarn 21d has been caused to form the same sequence of loops as yarn 21c but the loops of yarn 21d are out of alignment with the corresponding loops of yarn 21c. Yarn 21e has been caused to form 50 loops in another sequence, which includes two single loops followed by a double loop, a single loop, two double loops, and a single loop.

In the fabric of Fig. 10, the loops of pile yarn are 55 shown as having the shapes, in which they are maintained by the wires beneath them, but, when the wires are withdrawn from the transverse rows of loops, as the weaving operation proceeds, the elasticity of the yarns upon release of the tension therein causes the loops to decrease 60 in height. The single loops assume the shape of loop 37 (Fig. 11), while the double loops, such as loop 38, pull down to a less degree than the single loops. Accordingly, in the pile of the finished product, the single loops appear to provide a ground for a pattern formed by the 65 high multiple loops.

I claim:

1. A method of weaving carpets made up of pile and stuffer warp yarns and binder warp yarns in two sets interwoven with weft yarns on a loom equipped with a 70 jacquard mechanism, which comprises manipulating the warp yarns to form a first shed with all the pile yarns in the top line, the stuffer warp yarns and the binder warp yarns of the first set in the center line, and the binder warp yarns of the second set in the bottom line, inserting 75 a pile wire and a shot of weft yarn into said shed above

and below its center line, respectively, and beating up the wire and the shot, forming a second shed by lowering all the pile yarns and the stuffer warp yarns, while leaving the sets of binder warp yarns unchanged relatively to each other, selected pile yarns being lowered later than the remainder in the formation of the second shed whereby, in said shed, the binder warp yarns of the first set and said selected pile yarns lie in a line higher than the non-selected pile yarns, the binder warp yarns of the second set, and the stuffer warp yarns, inserting a shot of weft 10 yarn into the second shed, continuing the lowering of the selected pile yarns to place them in a line with the non-selected pile yarns, completing the lowering of the selected pile yarns, beating up the second weft shot, forming a third shed by raising all the pile yarns to a top line and the stuffer warp yarns and the binder warp yarns of the second set to a center line, while lowering the binder warp yarns of the first set to a bottom line, inserting a pile wire and a shot of weft yarn into the third 15 shed above and below its center line, respectively, and beating up the wire and the shot, forming a fourth shed by lowering all the pile yarns and the stuffer warp yarns, while leaving the sets of binder warp yarns unchanged relatively to each other, inserting a shot of weft yarn into the fourth shed below the binder warp yarns of the second set and above all the other warp yarns and beating up the shot, and repeating indefinitely the operations described in the order given.

2. The method of claim 1, in which the selected pile 20 yarns and the remaining pile yarns are separately raised to the upper line of the first shed and separately lowered in the formation of the second shed.

3. The method of claim 2, in which all the pile 25 yarns are raised in the same operation to form the top line of the third shed.

4. The method of claim 1, in which the raising of the selected pile yarns is started ahead of the raising of the remaining pile yarns and the lowering of the selected 30

pile yarns is started later than the lowering of the remaining pile yarns.

5. The method of claim 1, which is carried out on a loom equipped with a jacquard mechanism having a lash knot board and a comber board and in which selected pile 10 yarns are raised to the upper line of the sheds by the lash knot board and the remaining pile yarns are raised to said line by the comber board, and said selected pile yarns are lowered later by the lash knot board than said remaining pile yarns are lowered by the comber board.

6. In a method of weaving a carpet made up of pile and stuffer warp yarns and binder warp yarns in two sets interwoven with weft yarns on a loom equipped with a jacquard mechanism, the steps of forming a shed with the pile yarns in the top line, the stuffer warp yarns and the binder warp yarns of the first set in the center line, and the binder warp yarns of the second set in the bottom line, inserting a pile wire and a shot of weft 15 yarn into the shed above and below its center line, respectively, and beating up the wire and weft shot, forming a second shed by lowering all the pile yarns and the stuffer warp 20 yarns, while leaving the binder warp yarns unchanged, selected warp yarns being lowered later than the remainder, inserting a shot of weft yarn into the second 25 shed before said selected pile yarns have been fully lowered, said weft shot passing beneath said selected pile yarns and the binder warp yarns of the first set and above all the other warp yarns, and beating up the second weft shot.
